KEY HOLDER

John I. Hager and Eugene W. Samford,
Montebello, Calif.

Application December 2, 1947, Serial No. 789,204

4 Claims. (Cl. 70—456)

1

This invention relates to improvements in key holders of the type involving a case for enclosing several keys and means on the case for ejecting the keys for use, and the primary object of the invention is the provision of a key holder of this type which is more practical and serviceable in form and has more efficient key-ejecting means, a portion of which acts also to retain the unejected keys in place in the case.

Another important object of the invention is to provide a key holder of the above-indicated character wherein the key-ejecting means is operated against the tension of spring means in ejecting the keys for selection and use, and is operated by the release of the tension of said spring means in a manner to permit the ejected keys not selected for use to fall back into the case and be retained in position therein.

Another important object of the invention is the provision of a key holder of the above-indicated character in which a relatively unobtrusive button or finger-piece lying close to a side or edge of the case is slideable longitudinally of the case to effect the ejection of the keys when moved in one direction against the spring tension, and to effect positive retention of the keys in the case when released to be moved in the opposite direction by said spring tension, whereby mechanical superiority and reliability in action, as well as greater compactness are achieved.

Other important objects and advantageous features of this invention will be apparent from the following description and accompanying drawings, wherein, for present purposes of illustration only, a preferred embodiment of the invention is set forth in detail.

In the drawings:

Figure 1 is a side elevation of said embodiment, showing in dotted lines a key retained in the case;

Figure 2 is a longitudinal sectional view showing the mechanism in key-retaining position;

Figure 3 is a similar view showing the mechanism in key-ejecting position, with a key partly ejected from the case;

Figures 4 and 5 are transverse sections taken on the lines 4—4 and 5—5, respectively, of Figure 2.

Referring in detail to the drawings, the numeral 6 generally designates the key-holder case consisting of a molded plastic or other suitable material, elongated, narrow, generally rectangular body formed to provide two laterally-spaced plate-like sides 7, 7, and abbreviated bottom wall 8 extending therebetween and terminating short

2

of the adjacent end of the body at the point 9, and a block-like web 11 coextensive with and joining the opposite ends of the said sides. A removable type of pivot screw 12 traverses the sides 7, 7 in the region of the bottom opening defined by the termination 9 of the bottom wall 8 at the end of the case opposite the web 11 to permit keys 13 pivoted on the pivot screw 12 to swing in a wide arc not only through the upper opening between the said sides, but also through the bottom wall opening.

The juncture of the top of the bottom wall 8 with the web 11 is convexly curved so as to provide a conforming seat 14 for the normally reclining, comma-shaped key ejector arm 15, whose body portion 16 is traversed by a transverse pivot 17 whose ends are anchored in the sides 7, 7 at a point above and slightly forward of the seat 14, as shown in Figures 2 and 3. The elongated tapered tongue portion 18 of the ejector extends forwardly and normally lies along the bottom wall 8, as shown in Figure 2, with the unejected keys 13 resting gravitationally upon the tongue portion.

The inner surfaces of the sides 7, 7 are provided with parallel grooves 19, 19 extending rearwardly from a point midway of the length of the case 6 to the rear end of a rectangular recess 20 formed in the top of the web to accommodate movement longitudinally of the case of a button or finger-piece 21 which has ribs 22, 22 on its opposite lower sides slidably confined in said grooves. It is obvious that provision may be made for putting the button 21 and other mechanism in place by having one or both of the sides 7 separate from the web 11 and assembling them by suitable means, such as cementing, after the mechanism has been placed.

The button or finger-piece 21 has a generally rectangular cross-section and a longitudinally-curved and knurled upper edge 23 facilitating its manipulation, and projecting above the case 6 only far enough for convenient contact with a thumb or other finger.

The forward end of the lower edge of the button 21 has a depending lug 24 proportioned and arranged to engage the rounded front of the upper end of the body portion 16 of the ejector 15, as shown in Figure 3, when the button is pulled rearwardly, whereby the ejector tongue 18 is swung upwardly in a manner to lift and flip the keys 13 upwardly out of the case 6 to an elevated position in which they are held by the tongue 55 for selection of one or more of the keys by the

operator, as long as the button is held by the operator in the retracted position.

The rear end of the lower edge of the button 21 has a depending cam 25 having a forwardly-inclined face 26 for operative engagement with the rear upper curved part of the ejector body 16, whereby the ejector 15 is thrown downwardly from the elevated ejecting position shown in Figure 3 to the normal position shown in Figure 2, as the button 21 is moved forwardly from the 10 retracted position shown in Figure 3.

The forward movement of the button 21 producing the return of the ejector 15 to normal reclining position is effected by the expansion of a compressible helical spring 27 which has its forward end circumscribed on a pin 28 projecting rearwardly from the cam portion 25 of the button 21, and its rearward end inserted in a depression 29 in the rear wall of the recess 20; said expansion resulting from compression of the 15 spring by rearward pulling of the button 21 incidental to ejecting the keys 13 and taking place upon release of the button from retracted position.

The component parts are so proportioned and arranged that while the button is being held in retracted position and a selection of one or more of the keys 13 is made by swinging them over toward the left in the drawings, the remaining or unselected keys rest upon the tongue 18 of the ejector 15, as shown in Figure 3. When in these positions of the parts and the keys, the button 21 is released so as to be moved forwardly by the spring 27, the unselected keys fall gravitationally with the subsiding of the ejector sufficiently in advance of the arrival of the button 21 at its forward extreme position to permit the keys to fall to their lowest position before the button reaches them. The button 21 then rides forwardly to a position over the keys 13 and its forward lug 24 then acts as a limit stop, preventing the encased keys from having excessive movement or rattling relative to the case 6 and precluding their swinging out of the case while the selected key is being used or the holder is in the wearer's pocket.

We claim:

1. A key holder comprising a case open along one side edge thereof, a pivot pin for a key at one end of the case, an ejector lever in said case, a pivot for said ejector at the other end of the case, a lever actuating member slidable on the open edge of said case at said other end, a longitudinal arm on said lever underlying the key, an upwardly extending arm on said lever extending above the pivot thereof, spaced apart depending lugs on said lever actuating member engageable on opposite sides of said upwardly extending lever arm for rocking said lever, and spring means pressing said lever actuating member for retracting said lever within said case.

2. A key holder comprising a case open along one longitudinal edge thereof, a pivot pin for a

key at one end of the case, a key ejecting lever in said case including a longitudinal arm underlying the free end of the key, an upwardly extending arm on said lever at the other end of the case, a pivot for said lever below the upper end of said latter arm, a lever actuating member slidable on said other end of the case, a depending lug on the ends of said slideable member engaging on opposite sides of the upper end of said latter arm for rocking said lever, and spring means pressing said lever actuating member for retracting said lever into said case.

3. A key holder comprising a case open along one side edge thereof, a pin arranged transversely of said case adjacent one end thereof and fixedly supported within said case for rockingly supporting a key thereon, a key ejecting lever positioned longitudinally of and within said case intermediate said pin and the other end of said case and having one end adapted to engage a key when supported on said pin, said lever being mounted adjacent the other end thereof in said case for rocking movement about an axis transverse thereof, and hand actuatable means 25 positioned on said case adjacent the other end thereof engageable with the other end of said lever and mounted on said case for longitudinal movement toward and away from said pin to thereby effect the rocking movement of said lever.

30 4. A key holder comprising a case open along one side edge thereof, a pin arranged transversely of said case adjacent one end thereof and fixedly supported within said case for rockingly supporting a key thereon, a key ejecting lever positioned longitudinally of and within said case intermediate said pin and the other end of said case and having one end adapted to engage a key when supported on said pin, said lever being mounted adjacent the other end thereof in said case for rocking movement about an axis transverse thereof, hand actuatable means positioned on said case adjacent the other end thereof engageable with the other end of said lever and mounted on said case for longitudinal movement toward and away from said pin to thereby effect the rocking movement of said lever, and spring means operatively connected to said means for urging said lever toward said pin.
